UNITED STATES PATENT OFFICE

GEORGE W. HEENE, OF CLEVELAND, OHIO

MECHANISM FOR STAMPING MACHINES

Application filed February 13, 1929. Serial No. 339,687.

In stamping machines adapted to impress a name or emblem on a blank, it is customary to use a hammer or like member to strike a die by which the impression is made. Continued use of the machine brought about a condition wherein the dies became worn and the impressions or marks made thereby became less distinct and clear unless the intensity of the blow delivered by the hammer was increased or the dies were replaced. Replacement of the dies every time they became slightly worn necessitated frequent and unnecessary dismembering of the machine.

One object of my invention, therefore, is to provide means associated with the hammer of a stamping machine, whereby the hammer can be made to deliver blows of different intensity.

A further object of my invention is to place the intensity varying means in an easily accessible position so that adjustment can be made without disassembling the rest of the machine.

To be more specific, I provide a cam with a plurality of protruding points of different lengths, the cam being rotatably mounted to bring different points into contact with the hammer raising means. In this manner, as the die becomes worn, I propose to rotate the cam so that a longer point will engage the hammer raising means, thereby lifting the hammer to a higher position before it is released, whereby a blow of greater force will be delivered to the dies.

Another object of my invention is to provide a hammer of inexpensive and simple construction which is adapted to strike the dies a great number of blows without becoming worn or broken.

To be more specific, I construct my hammer of an iron casting and imbed therein a blow receiving portion of hardened material. By such a construction, the blow receiving means is adapted to withstand considerable shock while the remainder of the hammer is made from a less expensive material and in a simple manner.

Various other objects and advantages will in part become apparent and in part be here-

inafter set forth as the description of the invention proceeds.

For a full and more complete understanding thereof, reference may be had to the following description and accompanying drawings, in which:

Figure 1 is a side elevation of my stamping machine with the parts broken away and showing the application of this invention.

Figure 2 is a detail view in perspective showing an embodiment of my invention.

Figure 3 is a detail view with parts in section, and clearly shows the manner of mounting the cam and blow receiving means.

While a specific embodiment of my invention is herein set forth, it is understood that I am not to be limited by the exact construction described because various modifications of these details may be provided in putting the invention into practice within the purview of the appended claims.

Throughout the various figures of the drawings, like reference characters denote corresponding parts.

A stamping machine adapted to stamp a name or emblem on a piece of metal has a frame A upon which is carried supports 1. Also carried by the frame and rotatably connected thereto is a carrier in which are mounted dies 2. The dies 2 are pivotally secured at their inner ends, while their outer ends are held in a raised position by means of springs, (not shown), these springs being disposed between the dies and the die carrying member. Suitable means for rotating the die carrying member are also provided and carried by the upper portions of the supports 1.

A magazine for carrying metal discs is shown at 3 and comprises the tubular portion 4 and base member 5, the base member being adapted to rest on the frame A. A member 6 rigidly fastened to the frame A by the screws 7, has a cam 8 pivotally mounted thereto at 9, the cam 8 being adapted to clamp the base member 5 of the magazine 3 to the frame A. The operation of the cam 8 is the subject of a separate invention and is fully brought out in my Patent No. 1,738,-899, granted Dec. 10, 1929.

A metal disc upon which is to be stamped a name or emblem is supported by the member 10, which is provided with the ratchet 11 for consecutively turning the member 10 through small angles as the name or emblem is stamped on the aforementioned disc.

A hammer generally denoted as 12 is pivotally connected to a stationary part (not shown) of the frame for vertical swinging movement. The operative end of the hammer is provided with a weight 13 formed integrally therewith. A rotatably adjustable cam member in the form of a lug 17, having peripheral contact faces 18, 19 and 20 at different distances from its axis of rotation, is affixed to the hammer 12 by means of a pin 15 integral with the cam 17 and extending into a recess 14 of the said hammer 12. A screw 16 also carried by the hammer 12 and cooperating with screw threads therein, is adapted to abut against the pin 14, thereby preventing the cam 17 from rotating.

The under face or striking portion of the hammer 12 has a recess 21 therein into which is inserted a striker 22 of hardened material. The striker 22 is held in place by means of a pin 26.

A means 23 for raising the hammer 12 is pivoted to the frame (not shown) and has an end member 24 pivoted to the means 23 at 25. The end member 24 is so constructed that it is allowed to swing upwardly from the position as shown in Figure 1, but it is not allowed to swing below that position.

In the operation of a machine of this type, the raising means 23 is caused to pivot about its outer end (not shown). The end member 24 then engages one of the points of the lug 17 thereby lifting the hammer 12. Since the hammer 12 is also pivoted, the lug will describe an arc as it ascends, and a point will be reached where the cam 17 will disengage, thereby allowing the hammer 12 to descend under gravity action and strike the die which is below it. Then the member 23 is returned to its original position. When the dies become worn, the cam 17 is rotated so that one of the points 19 or 20 will be downwardly disposed. Since these points are longer than the point 18, the end member 24 will contact sooner with the points 19 or 20 on its upward movement, thereby raising the hammer to a higher position than before, and giving the hammer a greater distance to fall which, of course, will increase the force of the blow.

Having thus described my invention, what I claim as new and desire to secure by Letters Patent of the United States, is:—

1. In a stamping machine of the class described, the combination with a hammer, of means associated therewith for varying the intensity of impact thereof, said means including a rotatably adjustable cam member carried by the hammer.

2. A stamping machine of the class described, comprising, in combination, a hammer member, means associated therewith for varying the intensity of impact thereof, said means including a rotatably adjustable cam member carried by the hammer member, and means for engaging said cam member to actuate said hammer.

3. In a stamping machine of the class described, the combination with a gravity operated hammer member, of means associated therewith for varying the intensity of impact thereof, said means including a cam member, carried by the hammer, said cam member having a plurality of cam surfaces thereon, and means adapted to selectively engage said cam surfaces to actuate said hammer.

4. In a stamping machine of the class described, the combination with a hammer member, of means associated therewith for varying the intensity of impact thereof, said means including a rotatably adjustable cam member, said cam member having a plurality of cam surfaces thereon, said surfaces being positioned at different distances from the axis of rotation of the cam member.

5. In a device of the class described, the combination with a gravity operated hammer member, and operating means for raising the hammer member and releasing the same, of a cam member carried by said hammer having cam surfaces selectively engageable by said means to raise the hammer member to different heights and release the same to deliver blows of different intensities.

6. In a stamping machine of the class described, the combination with a gravity operated hammer member, and operating means for raising the hammer member and releasing the same, of a cam member having cam surfaces thereon arranged at different distances from its center, said cam member being rotatably adjustable in said hammer, said cam member being adapted to have said surfaces selectively engageable by said means to vary the height to which the hammer member is lifted.

7. In a stamping machine of the class described, a gravity operated hammer member, an operating member adapted to engage said hammer member to raise and release the same to permit said hammer to deliver a blow, and a cam member on one of said members said cam member being adjustable to vary the height to which said hammer member is lifted.

In testimony whereof I affix my signature.
GEORGE W. HEENE.
